UNITED STATES PATENT OFFICE.

CHARLES S. ANGERS, OF MILWAUKEE, WISCONSIN, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE RACK.

Application filed April 16, 1923. Serial No. 632,354.

This invention relates to shoe racks such as are commonly used in shoe factories for holding shoes between operations performed upon the shoes and for carrying them from 5 one place of operation to another.

In order to facilitate the handling of racks of the type referred to, the racks are usually mounted upon casters. One great source of trouble attending the use of such racks is 10 that the casters are frequently broken by striking a projection in the floor such as may be occasioned by an elevator slightly above or below the level of the floor. Shoe racks are also commonly provided with rectangular 15 iron frames, and in the use of such racks as heretofore constructed operators frequently have had their fingers injured by having them caught between the frames of two racks. The object of this invention is to 20 provide a rack of improved and simplified construction by use of which both of these troubles will be to a large extent, or wholly, avoided.

In view of this object and as illustrated, 25 the invention provides an improved rack comprising a rack frame having at each corner thereof a novel caster frame embodying a bumper, a caster and guards for protecting the caster.

30 The above and other features of the invention will be described in the specification and pointed out in the claim.

Referring to the accompanying drawings, 35 in which like characters of reference indicate the same parts in different views—

Fig. 1 is a perspective view of a shoe rack constructed in accordance with this invention;

Fig. 2 is a detail view of one corner thereof showing the side of the caster frame;

Fig. 3 is a similar view showing the end of the caster frame;

Fig. 4 is a top view thereof;

Fig. 5 is a bottom view thereof, and

Fig. 6 is a sectional view on the plan of line 6—6 of Fig. 2.

In these drawings 10 indicates a rectangular angle iron frame of a shoe rack which is provided with the shoe supporting members

11 and at its corners is mounted on swiveled 50 casters 12. Each caster 12 is mounted in or attached to a caster frame 13 preferably consisting of a metal casting shaped to fit the right-angular corner formed by the braced angle iron bottom and upright of the rack 55 frame 10. For this purpose the caster frame comprises a bottom, an upstanding side cheek 14 to fit outside of the upright flange of the bottom piece of the rack frame and an upstanding end part 15 to fit around the end 60 of the upright of the frame, all of these parts of the caster frame being at right angles to each other. The bottom portion of the caster frame may be secured to the bottom 65 of the rack frame by means of bolts 16. A pair of downwardly and inwardly extending 70 guard members 17, preferably integral with the caster frame and projecting from the bottom member thereof, are positioned as close to the caster as convenient without interfering with its swiveling action and extend down to near the floor, in practice about half an inch from the floor. The broad 75 rounded outer surfaces of these guard members 17, strengthened by the central inner web, form rack lifting cams which will engage and ride over obstructions in the path of the casters, such as the raised edge of an elevator floor, and so lift the shoe rack and its casters as to enable them to easily ride 80 onto such an obstruction without subjecting the casters to a blow above their centers which would be likely to break them, as with the shoe racks of ordinary construction.

Furthermore, the sides 14 and ends 15 of 85 the caster frames extend beyond the rack frame a considerable distance to form bumpers to strike parts of other shoe racks, either when run side by side or end to end, and so prevent the rack frames coming close 90 enough together to pinch the fingers between them.

What I claim as new and desire to secure by Letters Patent is:

In a rack, a rack frame, a caster frame secured to each corner thereof, a caster mounted in each caster frame, a bumper projection at the end and the side of each caster frame 95

for preventing rack frames from coming close enough together to pinch the fingers between them, and a pair of downwardly and inwardly inclined guard members at the front and the rear of each caster to serve as fixed cams for lifting the rack when striking an obstruction which would be likely to in-

jure the caster, the caster frame, bumper projection and guard members at each corner of the rack frame being of unitary construction. 10

In testimony whereof, I affix my signature.

CHARLES S. ANGERS.
